UNITED STATES PATENT OFFICE.

HENRY W. A. PRANGE, OF CHICAGO, ILLINOIS, ASSIGNOR TO NORTHWESTERN EXPANDED METAL COMPANY, OF CHICAGO, ILLINOIS, A CORPORATION OF ILLINOIS.

METAL BASKET.

Application filed March 29, 1923. Serial No. 628,496.

To all whom it may concern:

Be it known that I, HENRY W. A. PRANGE, a citizen of the United States, and a resident of Chicago, county of Cook, and State of Illinois, have invented certain new and useful Improvements in Metal Baskets, of which the following is a specification.

The invention relates to metal baskets of the type formed of a sheet metal strip that is slotted and expanded to form diamond mesh and seeks to provide an improved construction which is of uniform strength throughout.

The invention consists in the features of improvement hereinafter set forth, illustrated in the accompanying drawing and more particularly pointed out in the appended claims.

In the drawings:

20 Fig. 1 is a vertical section of the improved basket;

Fig. 2 is an enlarged detail view illustrating the manner of uniting the opposite edges of the expanded metal basket body; and

25 Fig. 3 is a section on the line 3—3 of Fig. 2.

The basket body *a* is formed of a single section or strip of sheet metal which has been slotted and expanded to form uniform diamond mesh having two series of oppositely inclined strands 10 united at their intersections by integral bonds 11. The corners of the opposite zig-zag or sinuous edges of the strip are united so that the original slits

30 of the sheet extend vertically of the basket body and the direction in which it has been expanded extends circumferentially thereof. It is also noted that when the strip is bent to cylindrical form the bonds 11 are ar-

35 ranged in planes slightly inclined to the radial. The basket body is usually further expanded in circumferential direction to form a flaring upper end and also to give it a gradual taper from top to bottom. Such

40 a structure, for the most part, is extremely rigid in vertical direction or at right angles to the direction of expansion and it can be readily braced circumferentially or in the direction of the expansion by securing suitable stiffening rings or the like to its upper and lower edges after it has been brought to the desired shape. Except at the sinuous or zig-zag edges of the expanded metal strip, the strand sections 10 between the transverse

rows of bonds 11 are quite short and hence 55 the body of the strip is quite rigid in vertical direction. But at its opposite sinuous edges the strand sections 10^a are of double length and difficulty has been encountered in providing a simple, strong, slightly joint between these edge portions. 60

In accordance with the present invention the corners or central portions of the double length strands 10^a at the opposite sinuous or zig-zag edges of the expanded metal strip 65 are overlapped, as most clearly indicated in Figs. 2 and 3, and the overlapped contacting portions of these strands are rigidly welded together, preferably by means of suitable electric welding devices. The contacting 70 corners or welded portions 12 of the meshes are in line with alternate transverse rows of the bonds 11 and form in effect bonds at the central portions of the strands 10^a of double length at the opposite sinuous edges of the 75 expanded metal strip. Hence, the strands and connections or bonds at the joined edges of the strip are substantially the same as the other strands and bonds and the entire basket body is substantially uniform in 80 structure, strength and appearance throughout. It is also noted that the welded portions 12 of the strands 10^a, like the bonds 11, are arranged in planes slightly inclined to the radial. Furthermore, this manner of forming the joint between the opposite edge 85 portions of the expanded metal strip can be readily and economically effected, and it is particularly well adapted to prevent distortion of the body when it is further expanded and shaped, as shown, to provide a 90 gradual taper and a flaring upper end.

After the basket body is formed as described, the portions of the strands at its upper and lower edges are bent around a pair 95 of metal stiffening rings 13 and a finishing strip 14 is bent or clamped upon the portions of the strands that encircle the ring 13 at the upper edge of the basket. The basket is provided with an imperforate sheet metal 100 bottom *b* having an upturned flanged edge 15 which is bent or clamped about the lower stiffening ring 13 and the lower outturned end of the expanded metal body. Preferably also, an imperforate sheet metal collar 105 *c* is snugly fitted within the lower portion of the basket body and is secured in position by gripping its outturned lower edge 16

between the edges of the basket body and bottom as shown, or by welding it to the bonds 11 at the lower edge portion of the basket body. The collar *c* is formed of a straight strip of imperforate sheet metal having its ends securely united by a suitable joint or seam 17 and having an outturned or flaring upper edge 18 that snugly engages the basket body.

10 Obviously, changes may be made in the details set forth without departure from the essentials of the invention as defined in the claims.

I claim as my invention:

15 1. A basket body comprising a sheet of expanded metal having diamond-shaped meshes with the outer side corners of the meshes at one edge of the sheet in line with the corresponding corners of the meshes at 20 the other edge of the sheet, the sheet being shaped into basket form and the meeting corners of the meshes welded together.

25 2. A metal basket comprising a body formed of a single sheet of expanded metal having diamond-shaped meshes with the outer side corners of the meshes at one edge of the sheet in line with the corresponding corners at the other edge of the sheet, the sheet being shaped into basket form and the 30 meeting corners of the meshes welded together, the direction of expansion of the sheet extending circumferentially of the basket, and a stiffening ring and a stiffening

bottom united to the upper and lower edges respectively of said body.

3. A basket comprising a sheet of expanded metal having diamond-shaped meshes with the outer side corners of the meshes at one edge of the sheet in line with the corresponding corners of the meshes at the other edge of the sheet, the sheet being shaped into basket form, of substantially uniform structure throughout, with the direction of expansion extending circumferentially thereof and with the meeting corners of the meshes welded together and arranged in planes slightly inclined to the radial.

4. A metal basket body comprising a single sheet of expanded metal having diamond-shaped meshes formed of two series 50 of thin, flat, oppositely inclined strands united at their intersections by rows of integral bonds and with the corresponding outer side corners of the meshes at the opposite edges of the sheet in line with one another and with alternate rows of bonds, the sheet being shaped into basket form and the portions of the strands forming the said outer side corners of the meshes over-lapped and welded together to provide a basket body of substantially uniform structure throughout with the direction of expansion extending circumferentially thereof and the bonds and welded portions slightly inclined to the radial, substantially as described.

HENRY W. A. PRANGE.
